UNITED STATES PATENT OFFICE

2,110,937

MANUFACTURE OF COVERS FOR ABRASIVE TOOLS

Frank Nown, Leicester, England, assignor to
United Shoe Machinery Corporation, Paterson,
N. J., a corporation of New Jersey

Application January 15, 1937, Serial No. 120,772
In Great Britain February 3, 1936

6 Claims. (Cl. 51—278)

This invention relates to the manufacture of covers for abrasive tools and is herein illustrated and described with relation to the preparation of an abrasive cover for a tool of the character disclosed in an application for United States Letters Patent Serial No. 755,962, filed December 4, 1934 in the name of Fred Ricks and Ernest Hope. This tool is of the rotary disk type but inasmuch as only the rim portion of the tool is utilized, the abrasive cover is formed from a strip of abrasive material applied to the rim portion only of the tool rather than from a relatively large sheet covering the face of the tool.

It is an object of the present invention to provide an improved method of making such abrasive covers. In accordance with the method shown herein, an abrasive cover for the rim of a rotary driven tool is made by securing together the ends of a strip of abrasive material to form a closed band and in molding the band while in moist condition by the application of internal pressure to a desired shape corresponding to that of the peripheral portion of the tool upon which the cover is to be applied. According to the method illustrated herein, a strip of abrasive-coated cloth is prepared with the edges of the strip in bias relation to the weave of the cloth; the ends of the strip are then cemented together to form a closed band with the abrasive coating on the outside; the band is then moistened and stretched to a desired shape by expansive pressure applied internally and it is maintained thus stretched until it dries to the desired shape.

A further object of the invention consists in the provision of an improved apparatus for making such abrasive covers. As shown herein the improved apparatus comprises a ring of rubber adapted to engage the interior of an abrasive band and means for expanding the ring to cause the ring to stretch the band. In the illustrated device, a ring of resilient metal is interposed between the rubber ring and the expanding means, the ends of the metal ring being in overlapping relation when the ring is unexpanded and arranged to snap into abutting relation when the rubber ring is expanded to its fullest extent, thereby to maintain the rubber ring expanded when it is removed from the expanding means. The illustrated apparatus for expanding the rubber ring comprises a plurality of members constructed and arranged for radial movement with respect to a common center, each of which members has an arcuate bearing surface for engaging the interior of the metal ring, the several

members being moved outwardly in unison by a cam mechanism.

With the above and other objects and features in view the invention will now be described with reference to the accompanying drawings and 5 pointed out in the claims.

In the drawings,

Fig. 1 is a plan view of a sheet of abrasive-coated woven fabric folded with two of its edges cemented together in overlapping relation, one corner of the sheet being shown as turned upwardly to indicate the direction of weave of the material as being bias relatively to the edges of the sheet;

Fig. 2 is a view in end elevation of the sheet 15 shown in Fig. 1, showing also a gage plate which may be used to assist in folding the sheet to the required size before cementing;

Fig. 3 is a plan view indicating a band cut from the sheet shown in Fig. 1; 20

Fig. 4 is a perspective view showing the band cut in Fig. 3 after it has been opened out into circular form;

Fig. 5 is a fragmentary view indicating the nature of the cemented joint; 25

Fig. 6 is a plan view of a forming or shaping member in unexpanded condition;

Fig. 7 is a sectional view taken along the line VII—VII of Fig. 6;

Fig. 8 is a view similar to Fig. 7 but indicating 30 a band in place on the unexpanded forming member;

Fig. 9 is a plan view of the forming member with a band thereon after the forming member has been expanded; 35

Fig. 10 is a sectional view taken along the line X—X of Fig. 9;

Fig. 11 is a perspective view of a completed cover member; 40

Fig. 12 is a plan view of an apparatus for use in expanding the forming member; and

Fig. 13 is a sectional view taken along the line XIII—XIII of Fig. 12 and showing a forming member with a band thereon in position to be expanded. 45

In Fig. 1 is shown a sheet 1 of woven fabric coated on one side with abrasive and cut in such a manner that the threads of the material, as indicated by the reference character 3, run in bias relation to the edges of the sheet. A 50 pair of opposite edge portions of the sheet have been folded in overlapping relation and glued together, a corner of the sheet being shown as turned over merely for the purpose of better illustration. The folding of the sheet to a pre- 55

determined size is readily accomplished by employing a gage plate 5 (Fig. 2) about which the sheet may be folded. As indicated in Figs. 1 and 5, the abrasive coating has been removed or preferably omitted from the underlying surface of the joint, while the overlapping edge extends just beyond the boundary of the under surface which is free of abrasive. We have found a joint prepared in this manner to be particularly efficient as regards resistance to wear. In gluing the edge portions of the sheet together it is desirable to subject the sheet to pressure while the glue sets in order to insure a firm joint. This may readily be accomplished by placing the assembly shown in Fig. 2 of the abrasive sheet 1 and the gage plate 5 between the platens of a suitable press. After the glue has set to form a firm joint the gage plate 5 is removed and the folded sheet 1 is cut through both its thicknesses along the lines indicated by the reference character 7 (Fig. 1) into a number of bands 9 (Fig. 3) of suitable width. The cutting operation may be performed by a guillotine knife equipped with a suitable gage to insure a uniform width for the bands. Each band 9 may then be opened out into circular form as shown in Fig. 4.

An expansible forming member 11 is used for imparting the desired molded shape to the band 9. This member, which is shown in unexpanded condition in Figs. 6 to 8, comprises an annulus 13 of rubber having a cross-sectional shape in general but not necessarily in exact correspondence to the cross-sectional shape of the abrasive tool body upon which the completed cover is to be used. Positioned against the inner surface of the annulus is an arcuate steel strip 15 which extends around somewhat more than half the circumference when the forming member is in unexpanded condition. Also located within the annulus 13 is a second arcuate steel strip 17 which, when the forming member is in unexpanded condition, is longer than the circumference of the adjacent internal surface of the annulus. The end portions of the strip 17 thus overlap when the forming member is unexpanded. In Figs. 6 and 7 the two ends of the strip 17 are indicated by the reference characters 19 and 21, respectively.

In using the forming member 11 the band 9 is placed thereon as indicated in Fig. 8. We have found it desirable that the band 9 should be in moistened or tempered condition during the shaping operation and also that the band 9 should be slightly smaller circumferentially than the periphery of the forming member. When the band is moistened it will stretch readily and hence can easily be drawn manually upon the forming member. As shown in Fig. 8, the band 9 is not applied centrally upon the forming member but one edge of the band is closer to the forming member than the other edge. This is because it is desirable in the finished abrasive cover that one edge portion of the abrasive cover should extend further inwardly than the other edge portion, as shown in Fig. 11. The operator in positioning the band 9 upon the forming member 11 can readily locate the band in the desired relation by bending downwardly, as indicated by the reference character 23, the upper edge portion of the band 9 to determine whether or not the edge registers with the internal surface of the forming member. The forming member is so designed that when the edge of the band thus reg-

isters the completed band will be of the desired shape.

After the band 9 has thus been mounted upon the forming member 11, the forming member is expanded by an apparatus which will presently be described. The expansion of the forming member stretches the rubber annulus 13 to the greater diameter shown in Fig. 9. As the forming member continues to expand, the overlapping ends 19 and 21 of the strip 17 will finally snap resiliently into abutting relation as shown in Fig. 9. The strip 17 will thereupon serve to hold the annulus 13 in expanded condition. The operator, when he so desires, can readily contract the annulus to its normal condition by flexing it to bring the ends 19 and 21 out of abutting relation. The strip 15 appears to assist in insuring that upon expansion of the forming member the ends 19 and 21 will assume and retain an abutting relation.

As a result of the expansion of the forming member the band 9 which, as above mentioned, will be in moistened or tempered condition, will be stretched and in the course of such stretching, by reason of the fact that the weave of the material is on the bias, the marginal portions of the band will turn inwardly closely to embrace the adjacent portions of the annulus 13. This effect is a result of the stretching action and does not require molding under pressure between dies. In Figs. 9 and 10 the band 9 is shown as having assumed its desired shape. The band 9 is preferably allowed to remain on the expanded forming member for about from three to six hours to allow the band to set into its molded shape. At the end of this period the operator contracts the forming member in the manner above indicated. The forming member can then be removed from the completed abrasive cover which is shown in Fig. 11. When the forming member is retracted and removed the band 9 does not contract, at least to any appreciable extent. The abrasive cover will thus have the predetermined circumferential size depending chiefly upon the length of the strip 17. The size may to a lesser extent depend upon the compressibility of the rubber of the annulus 13 but if bands 9 are originally formed of the same length and are made upon similar forming members in each of which the strip is of a uniform length, then there will be no appreciable variations in the circumferential size of the abrasive covers. A convenient size for abrasive covers for use in operations in the manufacture of shoes is six and one-quarter inches in diameter made from a band initially one and one-half inches in width.

The apparatus for expanding the forming member is shown in Figs. 12 and 13. This apparatus comprises a fixed circular base plate 25 on which a coaxial movable plate 27 in the form of an annulus is mounted. The plate 27 has a circumferential flange 29 by which it is retained in coaxial relation with respect to the base plate 25. The base plate 25 has formed therein two slots 31 at right angles to each other and each extending diametrically across the base plate. In each slot 31 there are movable two slide bars 33 retained in the slot 31 by screws 35 the stems of which are capable of sliding in narrow slots 37 in the base plate 25 and the enlarged heads of which are capable of sliding in wider slots 39 in the base plate. The inner end of each of the four slide bars 33 is provided with a segmentally-shaped member 41 which upstands above the surface of the base

plate 25 and is secured to its slide bar 33 by a screw 43 and pins 45. Each slide bar 33 has, near its outer end, a cam roll 47 upstanding therefrom and carried by a stud 49 passing through the bar and having a nut 51 on its upper end. The rolls 47 engage in arcuate slots 53 cut in the plate 27 and above the rolls on the studs 49 are washers 55 of larger diameter than are the slots 53. Thus the plates 25 and 27 are held together in assembled relation by the parts described. As shown in Fig. 12, the slots 53 extend in directions having both radial and tangential components. Bolted to the upper surface of the plate 27 is a laterally extending handle 57. The arrangement is such that on rotating the plate 27 by means of the handle 57 in a clockwise direction as viewed in Fig. 12 the slots 53 serve to move the cam rolls 47 outwardly. Thus the members 41 are also moved outwardly in unison.

In the use of the apparatus a forming member 11 with a band 9 thereupon is placed in the apparatus in the position indicated in Fig. 13, the members 41 being located in the space within the interior of the forming member and the lower surface of the band 9 resting against the base plate 25. The handle 57 is then manipulated to cause the members 41 to move outwardly as already described. These members will engage the inner surface of the strip 17, their surfaces which engage the strip being shaped, as seen in Fig. 12, to a curvature in general correspondence with that of the strip 17 when the forming member is expanded. The outward motion of the members 41 serves to expand the rubber annulus 13 until, as hereinbefore described, a stage is reached at which the ends 19 and 21 of the strip 17 come into abutting relation to maintain the forming member in expanded condition. The handle 57 may then be moved counterclockwise and the expanded forming member removed from the apparatus. This apparatus enables the expansion of the forming member to be performed quickly and easily.

Having thus described my invention, what I claim as new and desire to secure by Letters Patent of the United States is:

1. The method of making an abrasive cover for the rim of a rotary driven tool which consists in preparing an endless abrasive band of fabric with the weave of the fabric in bias relation to the circumference of the band, and in shaping the band by an expansive force applied from within the band.

2. The method of making an abrasive cover for the rim of a rotary driven tool which consists in making a strip of abrasive-coated cloth with the edges of the strip in bias relation to the weave of the cloth, cementing together the ends of the strip to form a closed band with the abrasive coating on the outside, moistening the band, stretching the band to a desired shape by expansive pressure applied internally of the band, and maintaining the band thus stretched while the band dries to the desired shape.

3. A device for shaping abrasive bands comprising a ring of rubber adapted to engage the interior of an abrasive band and to be expanded to stretch the band, and a ring of resilient metal 15 within said rubber ring, the ends of said metal ring overlapping when the rubber ring is unexpanded and abutting when the rubber ring is expanded, said metal ring with its ends in abutting relation serving to maintain said rubber 20 ring expanded.

4. A device according to claim 3 including also an arcuate strip of metal between the lapping ends of the resilient metal band and the interior of the rubber ring.

5. An apparatus for shaping abrasive bands comprising a ring of rubber adapted to engage the interior of an abrasive band, means for expanding said ring to cause said ring to stretch the band, and means for maintaining said ring 30 expanded after removal from said expanding means.

6. An apparatus for stretching abrasive bands comprising a pair of coaxial disks constructed and arranged for relative rotation, one of said disks having guideways extending outwardly from its central portion and the other disk having cam elements and having a central opening, a slide retained in each of said guideways by said disk, means on said slides in co-operative 40 engagement with said cam elements to cause outward or expanding movement of said slides upon relative rotation of said disks, and a member carried by each slide having an arcuate bearing surface adapted to engage the interior of 45 an article to be expanded, said work-engaging members extending through the central opening of said cam disk, and said arcuate surfaces when the work-engaging members are expanded having a common center in the axis of said disks.

50

FRANK NOWN.
